UNITED STATES PATENT OFFICE.

EINAR N. A. RAULAND, OF CHICAGO, ILLINOIS.

TRANSFORMER.

Application filed July 1, 1922. Serial No. 572,317.

To all whom it may concern:

Be it known that EINAR N. A. RAULAND, a citizen of the United States, and residing at 1516 North Lorel Avenue, Chicago, Illinois, has invented certain new and useful Improvements in Transformers, of which the following is a specification.

This invention relates to transformers and more particularly to transformers adapted for use in radio telegraphy and telephony.

It is the object of the present invention to provide a transformer of simple, sturdy and compact design and one which may be readily associated with and disassociated from a circuit in which it is to be used.

With this object in view the transformer constructed in accordance with the present invention is so arranged that its association with the circuit may be effected either by connecting the circuit conductors with the terminals of the transformer coils in the usual manner through the agency of binding posts or through a socket such as a lamp socket, and more particularly a type of socket adapted to receive an audion or other vacuum tube device. In accordance with the present embodiment of the invention, the contacts of the socket are engaged by said terminals acting as wipers or contact makers. Due to such arrangement, the transformer forming the subject of the present invention may be either mounted on a panel in the usual manner or inserted in a socket like a lamp or tube.

It should be noted also that the foregoing general description of the invention and the detailed description to follow are in no way intended to limit the scope of the present invention for which reference should be had to the appended claims.

In the drawings Fig. 1 is a side view and Fig. 2 a top view of a radio frequency transformer constructed in accordance with the present invention; Fig. 3 is a sectional view along lines 3-3 of Fig. 2; Fig. 4 shows the transformer core in perspective; Fig. 5 the mounting for the transformer core and Fig. 6 shows the socket arrangement to receive the transformer.

1 is a cylindrically shaped case of suitable material such as brass, having a closed top 2 in which four holes are provided for permitting the passage of lugs 3, 4, 5 and 6. The lower end of the case bulges out at 7 and an insulated bottom plate is set in the groove formed by bulge 7. The overhanging edge 9

of case 1 is then turned down on the bottom plate 8. The bottom plate 8 is provided with two ears 10 and 11 respectively, perforated at 12 and 13 respectively, the bottom plate 60 being set in place with the ears 10 and 11 engaging notches 14 and 15, respectively, cut out of the lower edge of case 1.

The primary and secondary windings of the transformer are provided on a cylindrical wooden core 16 and are wound within grooves 17 and 18 provided on the core. The core is perforated at 19 to facilitate the winding operation. The core 16 is held against a disc 20 of insulating material by 70 means of two screws 21, the distance between the core and the disc being determined by bushings 22. The screws 21 engage the core 16 at right angles to its axis and the grain of the wood, and to the right and left, respectively, of the grooves 17 and 18. Four holes 23 are provided in the disc for permitting passage of the lugs 3, 4, 5 and 6.

In assembling the transformer, after the core 16 is wound, it is secured to the disc 80 20 by means of the screws 21. The ends 24 and 25 of the primary and secondary windings are then secured to the lower ends of the lugs 3, 4, 5 and 6 and these lugs are pushed through the holes 23. The disc 85 is then set as shown in Fig. 3 against the top 2 of the case with the lugs 3-6 projecting through the holes provided therein. The axis of the core 16 is at right angles 90 to the axis of the case 1. The clearance between the holes provided in the top 2 and the lugs is filled in with washers 26 of insulating material. The protruding ends of the lugs are screw-threaded. By means of

95 nuts 27 engaging the screw-threaded portions of the lugs, the disc 20 is held securely against the top 2, washers 28 of insulating material separating the nuts 27 from the top 2. By means of thumb screws 29 and 30 engaging the screw-threaded ends of the 100 lugs, these lugs may be employed in the usual manner to act as binding posts for the conductors of a circuit with which the transformer is to be connected. In this case the transformer is fastened to a panel by 105 means of screws engaging the ears 10 and 11.

For the purpose of permitting the use of the transformer in combination with an audion tube socket 40, a lug 41 projecting from the case 1 is so located that when the transformer is inserted within the 110

socket 40 with the lugs 3—6 pointing downward and the lug 40 engaging an L shaped notch 42 in the socket, the desired connection will be had between lugs 3, 4, 5 and 5 6 and the contacts of the socket 40 which are, of course, suitably wired to the circuit.

The advantages of arranging the transformer to cooperate with a socket are manifold. First, the leads between the coils and the circuit with which it is to be connected are shortened as compared with the leads necessary in connecting a transformer mounted in the usual manner, whereby inductance and capacity losses that are caused by long leads are materially reduced; second, the transformer may be readily associated with the circuit; and third, the proper connection with the various parts of 10 the circuit is insured by the relative location of the coil terminals and the contacts of the socket. This rapid and accurate replacement of one transformer by another in a circuit is of particular importance in 15 radio receiving stations in which it is preferable to employ differently wound transformers (particularly radio frequency amplifying transformers) for different ranges of wave lengths.

20 For the purpose of further reducing inductance and capacity losses, the leads between the transformer coils and said terminals are also made as short as possible. In the present instance, this is accomplished 25 by the relative positioning of the transformer coils and the surrounding case. The case is of substantially cylindrical shape to fit within sockets of commercial type, and the transformer windings are provided on 30 a substantially cylindrical wooden or insulating core the axis of which is at right angles to the axis of the case. Due to this arrangement the transformer coil terminals or leading out wires are brought relatively 35 near the end of the case through which the terminal posts project. The case is preferably of metal such as brass and acts as a shield for the transformer.

40 The mentioned relative positioning of the case and core has also further advantages. The turns of the coils mounted on the core are on the average at a relatively great distance from the side walls of the case whereby eddy and other losses caused by induction, etc., are less than if said turns were nearer the case by mounting the core in the case coaxially.

45 Still a further advantage consists in making possible a simple mounting of the core without interfering with the efficiency thereof. In accordance with the present embodiment of the invention, this is accomplished by fastening the coil to the case, preferably through the agency of a disc of 50 insulating material, by suitable means such

as screws which engage the core at right angles to its axis, the disc being held against the top of the case through the agency of the terminal posts. As above stated, the core is preferably of wood (maple) and its 70 engagement by said screws at right angles to the grain of the wood will be less likely to cause splitting than if the screws were forced in the wood in the direction of the grain, and the screws will, of course, hold 75 better. Furthermore, if the core were coaxial with the case, it would be necessary to mount it by passing a screw, bolt or the like through the center thereof and therefore through the centre of the coils. As is 80 well known, this would cause eddy and other electrical losses. In the present case no metal need pass through the centre of the coils, the mentioned mounting screws projecting only to a slight distance within 85 the core and being located on the two sides of the coils. The metallic case within which the core is mounted has a closed top provided with four holes through which the terminal posts project. The core mounted 90 on the mentioned disc of insulating material is inserted through the open bottom of the case and then the case is poured full of some suitable sealing compound which will 95 protect the transformer coils against humidity, etc. The mentioned grooves in the core are not entirely filled with the transformer coils, and the sealing compound will be deposited in these grooves to seal in the coils.

100 Two notches are provided at the open end of the case and are so located as to receive two ears provided on a disc which serves as the bottom plate of the case. After the bottom plate is set in place the overhanging 105 edge of the case is turned down so as firmly to hold the bottom plate and to insure a proper clamping. This bottom plate is preferably of insulating material or is coated with some insulating compound whereby 110 eddy currents in the case will not find a complete circuit through which they may pass. In this connection it should be noted that the transverse mounting of the coils in the case causes the main induced currents 115 in the case to flow in the direction of the turns of the coil mainly through the longest possible path which is made longer by the insulation of the bottom plate.

120 In accordance with the present disclosure, the transformer is locked in a suitable socket by means of a bayonet joint connection. For this purpose a lug projects from the case and cooperates with an L shaped slot in the socket. The said two ears in the bottom plate are provided to serve as abutments for the thumb and index finger of the user when inserting the transformer in the socket. The ears are also perforated for facilitating 125 the mounting of the transformer on a panel. 130

It will be obvious to those skilled in the art that various modifications are practicable in the transformer structure forming the subject matter of the present invention without departing from the spirit thereof. The bayonet joint connection between the transformer case and the socket may be replaced by any other suitable connection. The terminal posts need not necessarily be provided in a manner to enable the use of this transformer in the conventional manner, and binding posts or contacts of any well known shape and arrangement may be used. While I found a substantially cylindrical wooden core satisfactory and most economical for the present purpose, cores of other materials and shapes may be used and still obtain some of the important advantages of the present invention.

20 What I claim is:

1. In a transformer adapted to be inserted in and to cooperate with a vacuum tube socket having four contacts, a substantially cylindrical case, a substantially cylindrical core within said case, the axes of said core and case being at an angle to each other, two transformer coils provided on said core adjacent to each other, and terminals for the transformer coils projecting substantially in the same direction through said case.

2. In a transformer adapted to be inserted in and to cooperate with a vacuum tube socket having four contacts, a substantially cylindrical case, a substantially cylindrical core within said case, the axes of said core and case being at right angles to each other, two transformer coil windings provided on said core substantially parallel to each other and at right angles to the axis of said core, and terminals for the coil windings projecting through one end of said case.

3. In a transformer adapted to be inserted in and to cooperate with a vacuum tube socket having four contacts, a cylindrical case, a cylindrical core within said case, the axes of said core and case being at right angles to each other, two transformer coil windings provided on said core substantially parallel to each other and at right angles to the axis of said core, and terminals for the coil windings projecting through one end of said case.

4. In a transformer, a cylindrical metal case, a cylindrical wooden core within said case, the axes of said core and case being at right angles to each other, and lugs projecting through one end of said case serving as a means for holding said core and as terminals for the coil windings.

5. In a transformer adapted to be inserted in and to cooperate with a vacuum tube socket having four contacts, transformer windings, a case enclosing said windings, contact points projecting from said case

and serving as terminals for said windings, all of said terminals arranged to engage the contacts of the socket.

6. In a transformer adapted to be inserted in and to cooperate with a vacuum tube socket having four contacts, transformer windings, a case enclosing said windings, contact points projecting from said case and serving as terminals for said windings, all of said terminals arranged to engage the contacts of the socket.

7. In a transformer adapted to be inserted in and to cooperate with a vacuum tube socket having four contacts, transformer windings, a case enclosing said windings, contact points projecting from said case and serving as terminals for said windings, a notch in said socket, a lug projecting from said casing and arranged to engage said notch to cause the cooperation of all of said contact points with the contacts of said socket in a predetermined manner.

8. In a transformer adapted to be inserted in and to cooperate with a vacuum tube socket having four contacts, a substantially cylindrical core carrying the transformer windings, a cylindrical case enclosing said core, the axis of the latter being at right angles to the axis of the case, contact points projecting through said case and serving as terminals for the transformer windings, all of said terminals arranged to engage the contacts of the socket.

9. In a transformer adapted to be inserted in and to cooperate with a vacuum tube socket having four contacts, a substantially cylindrical core, transformer windings mounted thereon, a cylindrical case enclosing said core, the axis of the latter being at right angles to the axis of the case, means for holding said core at a certain distance from one end of said case, four lugs projecting through said end of the case, the lower ends of said lugs serving as terminals for the transformer coils and the projecting ends as contact points or binding posts, a bottom plate for said case having two perforated ears, a notch in said socket, a lug projecting from said case and cooperating with said notch in such a manner that when said case is locked in place the four projecting lugs engage the contacts of said socket in a predetermined manner.

10. In a transformer adapted to be inserted in and to cooperate with a vacuum tube socket having four contacts, a substantially cylindrical core, parallel grooves at right angles to the axis thereof and containing the transformer windings, a cylindrical case enclosing said core, the axis of the latter being at right angles to the axis of the case, said case having a closed top and an open bottom, a circular disc of insulating

material within said case and between said core and the top, two screws for holding said core at a certain distance from said disc, four lugs projecting from the disc 5 through said top, the lower ends of said lugs serving as terminals for the transformer coils and the projecting ends as contact points and binding posts, an insulated plate for closing the bottom of said 10 case, a notch in said socket, a lug projecting from said case and cooperating with said notch in such a manner that when said case is locked in place the four projecting lugs engage the contacts of said socket in a pre- 15 determined manner.

11. In a transformer adapted to be inserted in and to cooperate with a vacuum tube socket having four contacts, an impregnated wooden core having a cylindrical 20 shape and being perforated through its centre, parallel grooves near the centre of said core at right angles to the axis thereof, transformer windings partly filling said grooves, a cylindrical metal case enclosing 25 said core, the axis of the latter being at right angles to the axis of the case, a top for said case, a circular disc of insulating

material within said case and between said core and top, a sealing compound filling said grooves and the open spaces between said core and case, two screws for holding said core at a certain distance from said disc 30 projecting through said disc and into said core at right angles to the grain of the wood and near the ends of the core, four 35 lugs projecting from the disc through said top, the lower ends of said lugs serving as terminals for the transformer coils and the projecting ends of said lugs being screw-threaded to receive binding post nuts, 40 washers of insulating material between said nuts and the top, notches in the open end of said case, an insulated bottom plate for said case having two ears engaging said notches, a substantially L shaped notch in 45 said socket, a lug projecting from said case and cooperating with said notch in such a manner than when said case is locked in place the four lugs engage the contacts of said socket in a predetermined manner. 50

In testimony whereof, I have signed my name to this specification this twenty-sixth day of June 1922.

EINAR N. A. RAULAND
